UNITED STATES PATENT OFFICE.

JOHN HAGBERG, OF TACOMA, WASHINGTON.

DESIGN FOR A GUITAR-BODY OR SIMILAR ARTICLE.

SPECIFICATION forming part of Design No. 29,666, dated November 15, 1898.

Application filed October 6, 1898. Serial No. 692,858. Term of patent 7 years.

To all whom it may concern:

Be it known that I, JOHN HAGBERG, a citizen of the United States, residing at Tacoma, in the county of Pierce and State of Washington, have invented and produced a new and original Design for a Guitar-Body or Similar Article; and I do hereby declare the following to be a full, clear, and exact description of the same, reference being had to the accompanying drawings, forming a part thereof.

In the accompanying drawings, Figure 1 represents a front elevation of a guitar-body or similar article embodying my design. Fig. 2 is a side elevation, and Fig. 3 is an end elevation, of the same.

The leading feature of my design consists of a hollow body portion which is formed with an extended trumpet-like projection having a sound-opening in its end and a central face-opening and provided with a neck portion carrying keys for regulating the tension of the playing-strings.

A in the drawings represents a guitar-body or similar article made in accordance with my invention having a body portion, as a , to which is attached a neck portion, as a' .

The neck portion extends upwardly and carries the usual keys, as a^2 , for regulating the tension of the playing-strings. The body portion a of the musical instrument is provided with a central face-opening, as a^3 . The body portion a is also constructed with an elongated extension, as a^4 , having a trumpet-like shape at the upper end of the said body portion, as at a^5 , at which point an opening is formed for the exit of sound. This extension a^4 extends along by the side of the neck a' and at a sufficient distance therefrom to not interfere with the playing of the instrument.

Having now described my invention, what I claim as new, and desire to secure by Letters Patent, is—

The design for a guitar-body or similar article, substantially as herein shown and described.

In testimony whereof I hereunto affix my signature in presence of two witnesses.

JOHN HAGBERG.
